A. G. TILLMAN.
TOOTH BRUSH HOLDER AND STERILIZER.
APPLICATION FILED MAY 8, 1916.

1,306,933.

Patented June 17, 1919.

UNITED STATES PATENT OFFICE.

ALBERT G. TILLMAN, OF VICKSBURG, MISSISSIPPI.

TOOTH-BRUSH HOLDER AND STERILIZER.

1,306,933.

Specification of Letters Patent. Patented June 17, 1919.

Application filed May 8, 1916. Serial No. 96,080.

To all whom it may concern:

Be it known that I, ALBERT G. TILLMAN, a citizen of the United States, residing at Vicksburg, in the county of Warren and 5 State of Mississippi, have invented certain new and useful Improvements in Tooth-Brush Holders and Sterilizers, of which the following is a specification.

My invention relates to a tooth-brush holder and sterilizer, for holding a tooth-brush and disinfecting the same when not in use; and also to a support for the receptacle, whereby the brush may be kept in 10 an aseptic condition.

15 Other objects of the device are to construct a neat, durable, efficient, article, that will have but few parts and may be easily and cheaply manufactured.

20 In the drawings forming a part of this specification, and in which like symbols of reference represent corresponding parts in the several views:—

25 Figure 1 is a sectional, longitudinal view of the invention in its operative position; Fig. 2 is a plan view of the removable partition for holding the germicide container in the cap;

30 Fig. 3 is a view of the regulating disk; Fig. 4 is a detail view, showing the connection of disk and partition;

Fig. 5 is a view of the handle for operating the regulating disk; and,

Fig. 6 is a view of the holder for the absorbent material.

35 In the drawings, 1 designates the casing, made of glass or other suitable material, to receive the tooth-brush; 2 a cap or closure for the same; 3 a ground bevel on the cap, corresponding to a ground bevel 4 on the 40 container. 5 is a ridge on the inside of the cap; 6 is a germicide holder adapted to receive absorbent material, such as cotton or wool, which is saturated with a liquid germicide. This germicide may be formed 45 as maldehyde, or the like, capable of giving off a vapor or gas. The holder is preferably formed as a ring with an annular flange 7 at its bottom to hold the material.

8 is a regulating disk, provided with a 50 central vent 9, and regulating vents 10. 11 is a removable partition, having outlets 12 adapted to register with vents 10 in the regulating disk, when the latter is turned through the medium of a handle 13. Handle

13 has shanks forming shoulders 14 and 15, 55 the latter resting against the face of partition 11, and 14 resting against the face of regulating disk 8. This prevents binding of the disk and partition when operated.

16 is a bracket having rings 17 and 18 60 adapted to receive the container 1 and the vial 19 which contains the sterilizing agent; and 20 the screw for connecting the bracket to its support. 21 is a ring or flange on the container 1 to hold it to its support; 65 and 22 a flange on the vial 19 to hold it in its support.

Partition 11 is made in the shape of a funnel at its center, which forms a pivot 70 for the regulating disk vent 9 which is made large to receive the point of the funnel. The disk and partition are open at the center, and the disk is also funnel-shaped to correspond and receive the center of partition. Openings 23 are formed by 75 leaves 24, said leaves being curved outwardly and then inwardly to increase the diameter of the partition and prevent it being forced into the chamber in the cap. 25 are three 80 purpose of holding the partition in its proper place by springing said leaves over the ridge or shoulder 5 in the cap.

My sterilizer may be made of glass, celluloid, metal, or wood. The flat surface on 85 the top enables the same to be placed in its inverted position when taken off the holder.

Having now fully described my invention, what I claim as new, and desire to secure by Letters-Patent, is:—

90 A toothbrush holder, comprising a receptacle for the brush, a ridge formed on the receptacle, a perforated partition formed with leaves extending from its sides, said leaves adapted to be sprung over the ridge 95 of the receptacle to support the partition, a disk operating in conjunction with the partition to regulate the perforations, and a ring formed with an annular flange to support absorbent material and to rest upon the 100 partition.

In testimony whereof I affix my signature in presence of two witnesses.

ALBERT G. TILLMAN.

Witnesses:

G. W. FORD,
ABE KRERAKY.
